(57) **CLAIM**

The ornamental design for a pedicure station, as shown and described.

DESCRIPTION

FIG. 1 is a perspective view of a pedicure station embodying my design;

FIG. 2 is a right side elevational view thereof, the left side elevational view being a mirror image thereof;

FIG. 3 is a top plan view thereof;

FIG. 4 is a rear elevational view thereof;

FIG. 5 is a front elevational view thereof; and,

FIG. 6 is a rear perspective view thereof.

The broken lines in the drawings are for illustrative purposes only and form no part of the claimed design.
